UNITED STATES PATENT OFFICE.

ARTHUR A. MERRITT, OF WORCESTER, MASSACHUSETTS, ASSIGNEE TO WILLCOX & GIBBS SEWING MACHINE CO., OF NEW YORK, N. Y., A CORPORATION OF NEW YORK.

SEWING-MACHINE.

1,253,507.

Specification of Letters Patent. Patented Jan. 15, 1918.

Application filed July 21, 1916. Serial No. 110,560.

To all whom it may concern:

Be it known that I, ARTHUR A. MERRITT, a citizen of the United States of America, and a resident of Worcester, Massachusetts, have invented a new and useful Improvement in Sewing-Machines, which invention is fully set forth in the following specification.

This invention concerns the adaptation to 10 the production of a felled seam of the type of machine commercially known as the Willcox & Gibbs Co. "Flatlock machine," shown for example in Merritt Patent No. 1,041,652, dated October 15, 1912; and more 15 particularly this invention has as its object the mounting of the folder at the free end of the work-arm, in a manner enabling it to be readily swung aside from its operative position in front of the needles to give access 20 to neighboring parts of the mechanism. As well-known, a felled seam is one in which two interfolded edges of fabric, brought into that relationship by passing through a folder, are secured together by 25 two parallel rows of stitches. One common and extensive instance of use of the felled seam is in men's linen shirts.

What is now believed to be the preferred embodiment of the invention is illustrated 30 in the accompanying drawing, wherein—

Figure 1 is a plan view showing the folder in operative position in front of the needles;

Fig. 2 is a similar view with the folder 35 swung aside out of operative position;

Fig. 3 is a longitudinal sectional view with some parts shown in elevation;

Figs. 4 and 5 are transverse sectional views on lines 4—4 and 5—5 respectively of 40 Fig. 1.

10 is a part of the free end of a hollow feed-off-the-arm work-arm of the kind more fully disclosed in the Merritt patent aforesaid; it includes a removable cover portion 45 11 having an opening covered by cloth-plate or throat plate 12 held in place by screws 13, 13. The parts acting upon the work above the cloth-plate include a plain hinged presser-foot 19 fulcrumed at 20 to foot-shank 16, the movement of the foot being 50 limited by stop-pin 21 working in said shank. Foot-shank 16 is secured to the lower end of presser-foot bar 17. 1 and 1^a are two eye-pointed needles working 55 through suitable slots in the presser-foot

and cloth-plate, and carried by needle-bar 2 (Fig. 3).

30 is a folder of a type well-known in the market for interfolding edges of fabric; it includes a base-plate 31 having slots through which screws 32 secure the folder to the horizontal arm 33 of a swinging carrier 34. The slots in base-plate 31 provide for adjustment of the folder toward and from the needles. Carrier 34 is hinged at one end on 35 a pin 35 extending between lugs 36, 36 formed on the rear-side of work-arm 11. The carrier 34, its socket at one end for the hinge pin 35, and the horizontal extension arm 33 at its other end, are preferably 40 formed in one piece by shaping and bending a single piece of sheet-metal. When in normal operative position, the folder and its swinging carrier stand in the position shown in Fig. 1, with the folder in front 45 of the needles and the arm 33 fitting in a recess 36' of cover 11, the parts being secured in this position by a latch 37 sliding in a plate 38 and retained in the plate by a stop-screw 39 projecting into a slot of the latch. 50 When, for any reason, it is desirable to get at the presser-foot, or to remove the cloth-plate for access to parts thereunder, latch 37 is withdrawn and the carrier 34 with folder 30 swung aside, as shown in Fig. 2. 55

The parts operating in the work-arm and beneath the cloth-plate, and as to which no patentable novelty is claimed herein, are substantially the same as corresponding parts in my aforesaid Merritt Patent No. 1,041,652 (see particularly sheet 35 of the drawings), dated in Osterhout Patent No. 1,134,483, dated April 6, 1915, except for differences herein mentioned. 40 is the looper lever, only the outer end of which is 60 shown; looper carrier 41, pivotally mounted thereon by a pivot-screw 42, carries two loopers 43, one for each of the two needles 1 and 1^a. Only one looper 43 is shown, Fig. 3. In the patents aforesaid, there are four 65 needles and four loopers. Looper-lever 40 fits, and is longitudinally movable, in a deep transverse recess in a cylindrical block 44 (Fig. 3) which is seated and rotatable in a circular recess in the bottom wall of the 70 work-arm—see sheet 19 of the drawings of the aforesaid Merritt patent. The looper-lever is given a longitudinal movement and a turning movement about the fulcrum provided by the rotatable block 44, both in a 75

horizontal plane, thereby imparting to the points of the loopers an elongated elliptical movement.

45 is a loop-spreader having a tail-piece 5 46, pivoting on a screw-pivot 47 and supported by a bracket-arm 48. A roller 49 on tail-piece 46 engages a cam-groove of a part 50 secured to the looper-lever 40, and thereby movement of the latter imparts sidewise 10 swinging movement to the loop-spreader 45 about its pivot 47. The paths of movement imparted to the loopers and loop-spreader differ somewhat from the paths of movement in the structures of the patents aforesaid, be- 15 cause the present structure produces two parallel rows of Grover and Baker stitches, with no crossing of threads between rows, as in the seams produced by the structures of said patents.

20 In said patents, two differentially operating feed-members are shown; one a fulling-feed, and the other a stitch-feed. In the present instance, only a stitch-feed member 60 is used. It is secured to and carried by a 25 feed-bar or lever 61, only the outer end of which is shown in Fig. 3.

In conjunction with the mechanism shown and described, I prefer to employ take-up means for the looper-threads such as disclosed in the pending application of Garrett B. Osterhout, Serial No. 127,180, filed October 23, 1916.

What I claim is:

1. In a sewing machine, the combination 35 with a work-arm having a free end, of stitch-forming mechanism operating at said free end of the work-arm, a folder-carrier positioned along one side of said free end of the work-arm and having a horizontal 40 extension lying across the top of the work-arm, a folder attached to said horizontal extension and normally positioned in advance of the stitch-forming mechanism, and a hinge-connection securing said carrier to

the work-arm and on which said carrier is 45 adapted to be swung to shift the folder from its said normal position to an out-of-the-way position removed from the stitch-forming mechanism.

2. In a sewing machine, the combination 50 with a work-arm having a free end, of stitch-forming mechanism operating at said free end of the work-arm, a folder-carrier positioned along one side of said free-end of the work-arm and having a horizontal ex- 55 tension positioned in a recess in the top of the work-arm, a folder attached to said horizontal extension and normally positioned in advance of the stitch-forming mechanism, and a hinge-connection securing 60 said carrier to the work-arm and on which said carrier is adapted to be swung to shift the folder from its said normal position to an out-of-the-way position removed from the stitch-forming mechanism. 65

3. In a sewing-machine, the combination with a work-arm having a free end, of stitch-forming mechanism operating at said free end of the work-arm, a folder-carrier positioned along one side of said free end 70 of the work-arm and having a horizontal extension positioned in a recess in the top of the work-arm, a folder attached to said horizontal extension and normally positioned in advance of the stitch-forming 75 mechanism, a hinge-connection having an upright axis securing said carrier at one end to the work-arm and on which said carrier is adapted to be swung to shift the folder from its normal position to an out-of-the-way position removed from the stitch-forming mechanism, and a detent at the other end of the carrier holding the same in normal position and adapted to release the carrier to swing on its hinge. 80 85

In testimony whereof I have signed this specification.

ARTHUR A. MERRITT.
